RAILWAY TIE AND RAIL CLAMP

John M. C. Bryant, Hopkins, Minn.

Application July 24, 1939, Serial No. 286,107

13 Claims. (Cl. 238—359)

My invention relates to improvements in metallic railway ties and rail clamps, and has for its object to provide a metallic railway tie that is relatively light in weight, strong, durable, and easy to put in place and assemble. This invention further provides a rail clamp that is relatively simple and positive in its action and easy to apply to a tie and rail. A further object of the invention is to provide a rail clamp that will automatically take up wear and thereby always securely hold a rail on a tie and cooperating pairs of these clamps will hold a pair of rails from spreading and will also hold the tie against endwise movement relative to the rails.

Other objects of the invention will be apparent from the following description, reference being had to the accompanying drawings:

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a fragmentary view in plan showing a pair of track rails resting on the improved railway tie and secured thereto by means of a pair of my improved rail clamps;

Fig. 2 is a view partly in transverse section and partly in elevation with the cover section of the tie removed;

Fig. 3 is a view partly in elevation and partly in section taken on the line 3—3 of Fig. 2, on an enlarged scale;

Fig. 4 is a fragmentary view of the tie as shown in Fig. 3, with the rail clamps removed and the sections of the tie segregated;

Fig. 5 is a fragmentary detail view in section taken on the line 5—5 of Fig. 2, on an enlarged scale;

Fig. 6 is a fragmentary plan view corresponding to the left hand end portion of the tie rail, shown in Fig. 2, but showing a modification of the tie;

Fig. 7 is a view partly in elevation and partly in section of the parts shown in Fig. 6 with the exception, that the cover section of the tie is removed; some parts are shown in different positions by means of broken lines;

Fig. 8 is a view partly in elevation and partly in section taken on the line 8—8 of Fig. 7;

Fig. 9 is a fragmentary detail view partly in plan and partly in section taken on the line 9—9 of Fig. 7, on an enlarged scale;

Fig. 10 is a fragmentary detail view partly in plan and partly in section on the line 10—10 of Fig. 9;

Fig. 11 is a fragmentary detail view partly in elevation and partly in section taken on the line 11—11 of Fig. 9; and

Fig. 12 is a fragmentary view of one of the end plates showing the spring cap seat therein.

Referring first to the improved metallic tie 13, shown in Figs. 1 to 5 inclusive, which is hollow and comprises a pair of substantially duplicate sections 14 and 15. These sections 14 and 15 are horizontally spaced and detachably connected by upper and lower interlocking joints 16. Each tie section 14 and 15 is folded from two-ply sheet steel and for the sake of convenience the sections 14 and 15 will hereinafter be referred to as body and cover sections respectively.

A pair of track rails 17 rest on the tie 13 and are secured thereto by a pair of my improved clamps as will hereinafter appear.

The tie 13, under each rail 17, is internally reinforced by a sleeve-like member 18 comprising sections 19 and 20 connected by upper and lower interlocking joints 21. Each reinforcing section 19 and 20 is made up of two-ply sheet steel folded internally onto the respective tie sections 14 and 15.

The several plies of each tie section 14 and 15 and its reinforcing section 19 and 20 are rigidly and permanently connected by spot welding or otherwise.

A flanged end plate 22 is seated against each end of each reinforcing member 18. Obviously each reinforcing member 18 and its end plates 22 afford a housing 23 for the respective rail clamp.

The tie sections 14—15 are detachably connected, at the reinforcing members 18, by a pair of nut-equipped headed bolts 24 which extend through aligned holes in the sides of said sections and reinforcing members.

Referring now to the hollow metallic railway tie 25, shown in Figs. 6, 7 and 8, which also comprises two horizontally spaced sections 26 and 27, connected by separable upper and lower interlocking joints 28. Each tie section 26 and 27 is folded from a single sheet of steel and the sections 26 and 27 will also be hereinafter referred to as body and cover sections. These tie sections 26 and 27 are detachably connected by a plurality of nut-equipped headed bolts 29 which extend through aligned holes in the sides of said sections.

A pair of track rails 30 rest on the tie 25 and are

secured thereto by the improved clamps. The tie 25, on each side of each rail 30, is internally reinforced by a flanged plate 31 which extends transversely through said tie. The reinforcing plates 31 are rigidly and permanently secured to the body section 26 of the tie 25 by spot welding or otherwise. A compartment 32 is formed in the tie 25, under each rail 30, by the respective pairs of reinforcing plates 31.

10. The clamps 33 used in connection with the two ties 13 and 25 are identical the one with the other and hence the description of the one will suffice for the other.

Referring to the clamp 33, shown in Figs. 6 to 12 inclusive, the same includes a pair of vertically disposed C-jaws in opposing relation. The jaws 34 are mounted in the compartment 32 and pivotally connected at 35 for opening and closing movements. The free end portions of the jaws 34 extend outwardly of the tie 25 through notches 36 in the top members of the sections 26 and 27 and transversely overlap the flanges of the rail 30, one on each side of the web of said rail. Formed with the pivoted ends of the jaws 34 is a pair of depending, edgewise spaced, crank arms 37.

A bell-crank 38 is pivoted at its elbow to each crank arm 37. One of the arms of each bell-crank 38 extends downwardly and is pivoted to an anchor bolt 39 and the other arms of the bell-cranks 38 extend horizontally away from each other and a horizontally disposed connecting rod 40 is pivoted thereto at its inner end. The outer end portions of the connecting rods 40 loosely extend through apertures in the reinforcing plates 31.

A nut acting spring cap 41 has screw threaded engagement with each connecting rod 40, outwardly of the respective plate 31. Said spring cap 41 has a relatively long cylindrical body 42, the inner end portion of which is wedge shaped, in a vertical plane as indicated at 43 and mounted on an open seat 44 in the respective plate 31.

Formed in the seat 44 are a pair of diametrically opposite notches 45, into which the end 43 of the body 42 extends and holds the spring cap 41 from turning on the connecting rod 40. The bolts 47 extend through aligned holes in the sides of the tie 13 and assist the bolts 24 in holding the sections of said tie in assembled relation.

50. A flat spiral spring 46 encircling the body 42 of each spring cap 41, is compressed between said spring cap and the respective plate 31.

The compressed springs 46, acting through the connections 40, 38 and 37, are under strain to yieldingly hold the jaws 34, pressed downwardly on the flanges 30 and thereby hold said rails pressed downwardly onto the tie 25.

The wedge shaped ends 43 of the bodies 42 are free to move in the seats 44 and permit swinging movement of the connecting rods 40 in a vertical plane.

As wear takes place between the rails 30 and the tie 25, between said rails and the jaws 34 and between the several parts of the clamps 33, said slack is automatically taken up by the tensioned springs 46. By adjusting the spring caps 41 on the connecting rods 40, the tension of the springs 46 may be varied at will. The novel construction of the springs 46 tend to materially increase the life thereof.

In placing the tie 25 under the rails 30, the body section 26, thereof, with the clamps 33 assembled therein and with the tension of the springs 45 released, is first placed under said rails

and the jaws 34 positioned on the flanges of the rails 30. Next the nut-action spring caps 41 are adjusted on the connecting rods 40 to compress the springs 46 to substantially their full limit.

Finally the tie cover section 27 is placed under 5 the rails 30 and secured to the body section 26 by the bolts 29.

Referring again to the invention, shown in Figs. 1 to 5 inclusive, the bell-cranks 38 are secured to the tie sections 14 and 15 by nut-equipped bolts 47. The jaws 34 work in notches 48 in the tie sections 14 and 15, and the connecting rods 40 extend through apertures in the end plates 22.

When the above described invention is used in 15 connection with an electric line, one of the rails 17 is insulated from the tie 13 as shown in Figs. 1 and 2. This insulation is accomplished by placing a plate 49 between the tie 13 and one of the rails 17 and which plate, together with the jaws 20 34 of the respective clamp 33, are made of fibre or any other suitable insulating material.

From the above description, it is evident that the tensioned springs 46, through the connections 40, 38, and 37, tightly press the rails on to 25 the tie and at no time permits vertical or horizontal movements of the rails relative to the tie. The springs 46 also automatically take up wear as the same takes place, and hence, prevents excessive wear. The interlocking engagement of 30 the bodies 42 of the nut-acting spring caps 41, at 43, 44, and 45, securely hold said caps from turning on the connecting rods under jarring action, produced on the rails by car-wheels turning 35 thereon.

It is highly important to note that the backs of the jaws 34 of each clamp 33 are always in direct contact with the tie 14 or 25 at the bottoms of the notches 36 or 48. Obviously the tie 14 or 25 acts as a base of resistance for the jaws 34 of 40 02 each pair and thereby positively holds the rails from spreading and the tie from endwise movement relative to the rails. As the jaws 34 of each clamp 33 automatically move toward each other, in taking up wear, the changing angularity of 45 03 their backs keeps said jaws in contact with the tie.

It will be understood that the invention described is capable of various modifications within the scope of the invention herein disclosed and 50 04 claimed.

What I claim is:

1. A device of the kind described comprising a pair of pivotally connected rail-engaging jaws, each jaw having a crank arm, a pair of bell 55 05 cranks pivoted at their elbows to the crank arms, means for pivotally connecting one of the arms of each bell crank to a railway tie and supporting the jaws for floating movement, and spring means for connecting the other arms of the bell 60 06 crank to the tie and under strain to move the jaws toward each other.

2. A device of the kind described comprising a pair of pivotally connected rail-engaging jaws, each jaw having a crank arm, a pair of bell cranks 65 07 pivoted at their elbows to the crank arms, means for pivotally connecting one of the arms of each bell crank to a railway tie and supporting the jaws for floating movement, a pair of connecting rods pivotally attached at one of their ends to 70 08 the other arms of the bell cranks and projecting in opposite directions therefrom, and spring means for connecting said rods at their other end to the tie and under strain to move the jaws toward each other.

3. A device of the kind described comprising a pair of pivotally connected rail-engaging jaws, each jaw having a crank arm, a pair of bell cranks pivoted at their elbows to the crank arms, means for pivotally connecting one of the arms of each bell crank to a railway tie and supporting the jaws for floating movement, a pair of connecting rods pivotally attached at one of their ends to the other arms of the bell cranks and projecting in opposite directions therefrom, and spring means encircling the rods and adapted to be compressed between abutments on the other end of said rods and relatively fixed parts on the tie through which said rods project, said spring means being under strain to move the jaws toward each other.

4. The combination with reinforced members adapted to be mounted in a hollow railway tie, of a rail clamp comprising a pair of pivotally connected rail-engaging jaws, each jaw having a crank arm, a bell crank pivoted at its elbow to each crank arm, means for pivotally connecting one of the arms of each bell crank to a railway tie and supporting the jaws for floating movement, a pair of connecting rods pivotally attached at one of their ends to the other arms of the bell cranks and projecting in opposite directions therefrom, and a spring encircling the rods and compressed between abutments on the other ends of said rods and said reinforcing members, said rods projecting through said reinforcing members.

5. A device of the kind described comprising a reinforcing sleeve adapted to be mounted in a hollow railway tie, and an end member seated against each end of the reinforcing sleeve, a rail clamp in the reinforcing sleeve and comprising a pair of pivotally connected C-shaped jaws in opposing relation, a crank arm on the pivoted end of each jaw, a bell crank pivoted at its elbow to each crank arm, one of the arms of each bell crank being pivoted relative to the reinforcing sleeve, a pair of connecting rods pivotally attached at one of their ends to the other arms of the bell cranks and projecting in opposite directions therefrom and through apertures in the end members, and flat spiral springs encircling the connecting rods outwardly of the end members and compressed between abutments on said rods and the end members, said springs being under strain to move the jaws toward each other.

6. A device of the kind described comprising a pair of members adapted to be mounted in a hollow railway tie and spaced longitudinally thereof, a rail clamp between said members and comprising a pair of pivotally connected rail engaging jaws, each having a crank arm, a bell crank pivoted at its elbow to each crank arm, one of the arms of each bell crank having means for pivotally holding the same relative to the tie, a pair of connecting rods extending through apertures in said members and pivotally attached at their inner ends to one of the arms of the bell crank, nut-acting spring caps having screw threaded engagement with the outer end portions of the connecting rods, said spring caps having relatively long bodies, said bodies having separable interlocking engagement with said members and thereby holding the spring caps from turning on the connecting rods and springs encircling said bodies and compressed between the spring caps and said members, said springs being under strain to move the jaws toward each other.

7. The combination with a tie and a rail having a web and base flanges projecting from opposite sides thereof and resting on the tie, of a rail clamp comprising a pair of jaws engaging the upper faces of the flanges, said jaws being pivotally connected for floating movement in the plane thereof and relative to the tie, and yielding-means under strain to close the jaws and press the same downwardly on the flanges and hold the rail on the tie.

8. A hollow railway tie, a clamp mounted in the tie and including a pair of rail engaging jaws, said jaws being pivotally connected for floating movement in the plane thereof and relative to the tie, and automatic means for moving said jaws toward each other, said jaws having contact with the tie as a base of resistance for holding the rail against lateral movement on the tie and for holding the tie against endwise movement relative to the rail, said clamp being resiliently secured to the tie by means under strain to close the jaws.

9. A hollow railway tie, a clamp mounted in the tie and including a pair of rail engaging C-jaws in opposing relation, said jaws being pivotally connected for floating movement in the plane thereof and relative to the tie, the backs of said jaws having direct contact with the tie as a base of resistance for holding the rail against lateral movement on the tie and for holding the tie against endwise movement relative to the rail, said clamp being resiliently secured to the tie by means under strain to close the jaws.

10. The combination with a tie and a rail having a web and base flanges projecting from opposite sides thereof and resting on the tie, of a rail clamp comprising a pair of pivotally connected jaws engaging the upper faces of the flanges, a pair of toggle-joints in opposing relation and pivotally connecting the jaws to the tie for floating movement, one of the members of each toggle-joint being rigidly secured to the respective jaw, and spring means connected to the tie and under strain to buckle the toggle-joints and move the jaws toward the web of the rail and also to pull the same downwardly onto the flanges of the rail.

11. The structure defined in claim 10 in which the toggle joints support the jaws for turning movement in the plane thereof and about the axis of the pivot connecting said toggle joints to the tie.

12. The combination with a tie and a rail having a web and base flanges projecting from opposite sides thereof and resting on the rail, of a rail clamp comprising a pair of pivotally connected C-shaped jaws in opposing relation, the free end portions of the jaws engaging the upper faces of the flanges, a pair of toggle-joints in opposing relation and pivotally connecting the jaws at their pivoted ends to the tie for floating movement, one of the members of each toggle-joint being rigidly secured to the respective jaw, and spring means connected to the tie and under strain to buckle the toggle-joints and pivotally move the free end portions of the jaws toward each other and the web and also pull the same downwardly to the flanges of the rail.

13. The structure defined in claim 12 in which the spring means also holds the jaws with their inner intermediate portion pressed against the longitudinal edges of the flanges and the rail clamped therebetween.

JOHN M. C. BRYANT.
